Inventor

UNITED STATES PATENT OFFICE.

ALBERT P. GUMAER, OF EAST ORANGE, NEW JERSEY.

PORTABLE SHOWER-BATH APPARATUS.

1,392,495.

Specification of Letters Patent.

Patented Oct. 4, 1921.

Application filed February 28, 1921. Serial No. 448,381.

To all whom it may concern:

Be it known that I, ALBERT P. GUMAER, a citizen of the United States, residing at 11 Wayne Ave., East Orange, in the county of Essex and State of New Jersey, have invented certain new and useful Improvements in Portable Shower-Bath Apparatus, of which the following is a specification.

This invention relates to a portable shower bath apparatus which can be readily attached to, and erected on any of the ordinary forms of bath tubs now in use, and which can be readily folded into a compact shape, and carried by travelers and others within their ordinary baggage.

There are various other advantages incident to the construction shown, and these will appear from the description to be given in connection with the accompanying drawings, illustrating one embodiment of my invention, which however, is susceptible of modification in various respects, it being understood that many changes may be made in the size and proportion of the several minor parts, as well as certain changes in details of construction, all within the scope of the invention.

In the accompanying drawings;

Figure 1 represents a side elevation partly in section of my apparatus.

Fig. 2 represents a plan view of the apparatus.

Fig. 3 represents a vertical section of the discharge rose and conduit.

Fig. 4 is a detail view partly in section of the coupling connecting the discharge conduit supporting standard.

Fig. 5 is a detail view partly in section of the slidable joint of one of the supporting standards.

Fig. 6 is a sectional detail view of the terminal of the supporting standard.

Fig. 7 is a detail of the hinged connections of the upper ends of the supporting standards.

Similar reference numerals indicate corresponding parts throughout the several figures of the drawings, wherein 1 represents the usual form of bath tub to which my improved apparatus can be applied.

2 represents the tubular supporting standard through which water is carried from the hot and cold water spigot 3, by the flexible conduit 4, which is detachably connected to the spigot 4, at the one end, and permanently attached at the other end to

the lower terminal of the tubular supporting standard 2.

Attached to the upper end of the supporting standard 2, is the T fitting 5, attached to the opposite end of the fitting 5 and screw threaded therein, is the hinge member fitting 6, provided with hinge knuckles 7 and 7'. Attached to the knuckles 7 and 7' are the upper terminals of the supporting standards 8 and 8'.

Attached to the T fitting 5 and screw threaded into the side outlet thereof, is the nipple 9, screw threaded on the nipple 9 is the discharge rose 10, a form of spray discharge well known in the art.

Located on the lower terminals of the supporting standards 2, 8 and 8' are the crow feet 11, adapted to conform with and rest on the curbed rim 12 of the tub 1.

For the purpose of reducing the lineal dimensions of the supporting standards 2, 8 and 8' suitable joints are provided therein as shown in Figs. 4 and 5. The joint shown in Fig. 4 pertains to the tubular supporting standard 2, through which the water is carried from the spigot 3 to the discharge rose 10, and comprises a well known form of pipe fitting union, 13 to which I have attached thumb wings 14, to facilitate setting up the union 13 without the use of a wrench or other implements.

The supporting standards 8 and 8' comprise two sections wherein the lower section of each, is adapted to slide within the upper section, and as shown in Fig. 5, the upper or exterior section is provided at its lower end with an enlarged boss 15, into which is screw threaded the thumb screw 16, adapted to apply a bearing contact on the surface of the lower or interior section of the standard slidably mounted within the boss 15.

By means of the joints in the standards 2, 8 and 8', shown in Figs. 4 and 5, and the hinge joint shown in Fig. 7, admitting the upper sections of standards 8 and 8' to fold over and assume a parallel position with the upper section of the supporting standard 2, my apparatus can be folded into a compact form.

Another feature which my improved apparatus admits of is an adjustment of elevation of the discharge rose to conform to the wishes of the user, by the adjustment of the slidable joints of the standards 8 and 8', and by the farther spacing apart of the

lower terminals of the standards at different positions on the tub, allowing for its use by juveniles as well as adults.

When it is desired to erect and use my portable shower bath apparatus, the lower extensible sections of the supporting standards are extended to the desired position, and the union 13, on standard 2 is set up, and the thumb screw 16 is set up on the standards 8 and 8'. The crow feet 11 attached to each of the standards 2, 8 and 8', are placed upon the curved rim 12 of the tub 1, and the flexible conduit 4, is suitably attached to the discharge nozzle of the spigot 3. The usual form of spigot 3, is provided with a dual feed of hot and cold water, whereby the temperature of the water as well as the force of the flow may be regulated in the usual way, thus regulating the temperature and the force of the flow of the shower spray emanating from the discharge rose 10.

The shower bath apparatus is prepared for packing and transporting by telescoping the extensible sections of the standards 8 and 8', and by disconnecting the union 13 of the standard 2, and folding the upper sections of the standards 8 and 8' over and parallel with the standard 2.

The lower section of the standard 2 likewise folds parallel with the other sections, and the discharge rose 10 may be unscrewed from the nipple 9, thus reducing the cubical dimensions of the apparatus at this point, and enabling the entire apparatus to be folded into a compact shape.

While I have herein described and illustrated the best form of the invention now known to me, it will be apparent to those skilled in the art, that changes may be made in the form of apparatus disclosed, without departing from the spirit of my invention.

Having described my invention, what I claim as new, and desire to secure by Letters Patent is:

1. In a portable shower bath apparatus, the combination with a stationary bath tub including a discharge faucet, of jointed sup-

porting standards removably attached thereto having hinged connections at their upper ends and supporting a spray discharge member therefrom, a conduit located within one of said supporting standards terminating in a detachable flexible connection with said faucet and adapted to convey water there- 55 through to said spray discharge member.

2. In a portable shower bath apparatus, the combination of jointed supporting standards having supporting brackets at their lower ends for mounting on a bath tub rim, 60 hinge members connecting the upper ends of the same, a water conduit located within one of said standards terminating in a detachable flexible member adapted for connection with the discharge faucet of said 65 bath tub.

3. In a portable shower bath apparatus, the combination of jointed supporting standards having supporting brackets at their lower ends for mounting on a bath tub rim, 70 hinge members connecting the upper ends of said standards, a detachable spray discharge member attached to one of said standards, a water conduit located within the last mentioned standard, terminating in a detachable flexible member adapted for connection with the discharge faucet of said bath tub. 75

4. In a portable shower bath apparatus, the combination of jointed supporting standards having supporting brackets at their 80 lower terminals for mounting on a bath tub, hinge members connecting the upper ends of the same, a detachable spray discharge member depending from one of said standards means for conveying water under pressure to said discharge member, and means for adjusting the relative elevation of the discharge member above the bath tub substantially as described. 85

In testimony whereof I have affixed my 90 signature in the presence of two witnesses.

ALBERT P. GUMAER.
